UNITED STATES PATENT OFFICE

FRANCIS W. GIBSON, OF WEST ROXBURY, MASSACHUSETTS

DESIGN FOR A DISPLAY RACK

Application filed October 27, 1930. Serial No. 37,399. Term of patent 3½ years.

To all whom it may concern:

Be it known that I, FRANCIS W. GIBSON, a citizen of the United States, residing at West Roxbury, in the county of Suffolk, Commonwealth of Massachusetts, have invented a new, original, and ornamental Design for Display Rack, of which the following is a specification, reference being had to the accompanying drawing, forming part thereof.

The figure is a perspective view of a display rack showing my new design.

I claim:

The ornamental design for a display rack, as shown.

FRANCIS W. GIBSON.
